[57] CLAIM

The ornamental design for a tool for gripping a sprinkler nipple, or similar article, substantially as shown and described.

DESCRIPTION

FIG. 1 is a front elevational view of a tool for gripping a sprinkler nipple with jaws that pivot past each other, or similar article, showing my new design.

FIG. 2 is a right side elevational view thereof.

FIG. 3 is a rear elevational view thereof.

FIG. 4 is a left side elevational view thereof.

FIG. 5 is a bottom plan view thereof.

FIG. 6 is a top plan view thereof.
